UNITED STATES PATENT OFFICE.

MADDRA J. HEWLETT, OF KEWANEE, ILLINOIS, ASSIGNOR OF ONE-HALF
TO ALFRED M. HEWLETT, OF KEWANEE, ILLINOIS.

ROTARY ENGINE.

SPECIFICATION forming part of Letters Patent No. 696,904, dated April 1, 1902.

Application filed October 26, 1900. Serial No. 34,491. (No model.)

To all whom it may concern:

Be it known that I, MADDRA J. HEWLETT, a citizen of the United States, residing at Kewanee, in the county of Henry and State of Illinois, have invented a new and useful ⁵ Rotary Engine, of which the following is a specification.

My present invention relates to a novel motor or other analogous translating device.

10 In order that the invention and the special utility underlying it may be better comprehended, attention may be called to the fact that motors, air-compressors, pumps, or other translating devices embodying rotary pistons ¹⁵ driven by a motive fluid or subjected to back pressure exerted thereby have been more or less unsatisfactory, particularly in connections where the direct or back pressure is necessarily great. The truth of this state-

20 ment is particularly apparent to those familiar with the development of rotary engines, and the principal reason underlying this debility of translating devices of this character is that the rotary member or piston is not ²⁵ only subjected to pressure in the line of movement of its periphery, but is also subjected to a corresponding side pressure exerted toward its axis. This will be more clearly apparent when we consider that in devices of

30 the type mentioned the rotary member is driven by the impact of the motive agent against blades or heads extending radially from its periphery or against substantially radial abutments formed by recessing the

35 periphery of the member. It follows, therefore, that the liberation of an expansive fluid in effective proximity to this member or piston will necessarily exert what is known in the art as "side pressure," tending to create a

40 degree of friction between the rotary piston and its shaft or between the shaft and the shaft-bearings, increasing in like ratio as the effective pressure of the motive agent is increased. The same result is noticeable when

45 the rotary member, instead of being driven by an expansive agent under the direct pressure thereof, as in rotary engines, is employed, for instance, for compressing air or for pumping water, because in these rela-

50 tions the fluid compressed or pumped exerts a back pressure, which to all intents and

purposes is the equivalent of the direct pressure exerted by a motive agent, at least in so far as the side pressure and consequent friction is concerned. Obviously, therefore, a ⁵⁵ type of devices which are capable of rendering efficient service under low pressure and when subjected to light loads are prohibitively inefficient when subjected to high pressure and burdened with a considerable load. ⁶⁰ A striking evidence of this fact is the common necessity for turning over a rotary engine manually or otherwise after the throttle has been opened in order to secure its response to the introduction of the motive ⁶⁵ agent.

Having in mind, therefore, the elimination of this objectionable element in engines or other translating devices of the rotary type, the object of my invention is to produce a ⁷⁰ simple and effective construction by means of which a counteractive pressure may be opposed to the side pressure of the fluid directed against the outer periphery of the piston, and, further, to so organize and arrange a series ⁷⁵ of rotary elements as to totally eliminate the objectionable side pressure defined, to provide for a decrease of the area of the pistons in frictional contact with the sides of the casting, and to include in such a device a novel ⁸⁰ form of controlling-valve serving to regulate, either automatically or otherwise, the supply of a motive agent to the motor.

To the accomplishment of the several objects stated, the invention consists in the construction and arrangement of parts hereinafter fully described, illustrated in the accompanying drawings, and succinctly defined in the appended claims.

In said drawings, Figure 1 is a sectional elevation of what is perhaps the simplest embodiment of my invention. Fig. 2 is a similar view of a variation which comprehends an increase in the number of radial heads upon the center piston, the inclusion of a ⁹⁰ novel controlling-valve, and the addition of a supplemental steam-induction port intended to be utilized to start the motor. Fig. 3 is still another variation, the peculiarities of which will be defined hereinafter. Fig. 4 is ⁹⁵ a similar view of still another variation. Fig. 5 is a sectional view on the line ¹⁰⁰ 5 5 of Fig. 4,

and Fig. 6 is a detached view of one of the casing-heads.

Referring to the numerals employed to designate corresponding parts throughout the views, but having more general reference at present to the structure shown in Fig. 1 of the drawings, 1 indicates the casing of a rotary engine, which type of translating devices I have selected for the purpose of illustrating the application of my invention. This casing is given any requisite form in accordance with the number and relative proportions of the rotary members, which in this instance are embodied in the piston-wheels 2, 3, and 4. 15 The several wheels are mounted within the casing 1 upon shafts 2', 3', and 4', which are provided with suitable bearings in the opposite sides or heads 5 and 6 of the casing and are geared to a driving-shaft 7—as, for instance, in the manner shown in Fig. 5 of the drawings. In this embodiment of the device the center piston 3 has its periphery in contact with the periphery of the end pistons 2 and 4 and is provided at diametrically opposite points with a pair of radially-extending piston heads or blades 8 and 9, arranged to extend into peripheral recesses 8^a and 9^a and 8^b and 9^b in the piston-wheels 2 and 4, respectively. The heads 8 and 9 are designed 25 to receive the impact of steam or other motive agent to effect the rotation of the center wheel and through it the end wheels 2 and 4, and it is therefore necessary to define a closed steam-space through which the heads 30 may move when passing from one side to the other, or, in other words, between their points of engagement between the end wheels or pistons. This steam-space, or, more properly speaking, these steam-spaces 10 and 11, I define by mounting a pair of head-blocks 12 and 13 within the casing and extending between the heads with their concave faces concentric with the periphery of the wheel 3, but at a sufficient distance therefrom to have steam-tight engagement with the outer ends or faces of the heads 8 and 9 as the latter are impelled under steam or other pressure. One end of each head-block is disposed in steam-tight connection with the periphery of an end 45 wheel or piston, and at the other end of each block is formed an exhaust-passage 14 or 14', designed to lead the steam from the steam-spaces to the exhaust-ports 15 and 16 through the wall of the casing. 50 Anticipating for a moment the description of the means which I employ for effecting the introduction of the motive agent to the interior of the casing, it will be noted that the liberation of steam or other expansive fluid 55 within the steam-spaces will be effected immediately behind the heads 8 and 9, assuming the parts to be positioned as in Fig. 1. The adjacent contacting portions of the walls or peripheries of the wheels will constitute 60 an abutment confining the steam for the effective exertion of its pressure against the heads, which are shown as just entering the

steam-passage. A continuation of this pressure will cause the heads to move through the steam-spaces toward the exhaust-passages 70 at the farther ends thereof; but it will also appear that the pressure which is exerted upon the head to drive the center wheel or piston will be exerted in like degree upon the peripheries of the several wheels in the directions of or rather toward their axes. The effect of this upon the center wheel will be to balance it, inasmuch as the pressure of the steam occluded in each steam-passage will exert corresponding side pressures in opposite 80 directions at diametrically opposite points; but no such desirable counteraction is exerted upon the end wheels or pistons for the reason that at a point diametrically opposite the point of exertion of pressure thereon these 85 wheels are either subjected to no steam-pressure at all or are opposed to clearance-spaces in communication with the exhaust, and consequently containing either no motive agent or only such as will exert no effective counteractive pressure. It is evident, therefore, that there will be a side pressure or thrust exerted upon the bearings of the shafts 2' and 4', creating an obstructive friction corresponding to the steam-pressure, and it will therefore follow that a large proportion of the energy designed for translation will be consumed in overcoming this frictional resistance to the operation of the motor, and it will be equally clear that the elimination of 95 this friction will correspondingly increase the capacity and range of utility of the engine. The manner in which I effect the elimination of this objectionable feature is by subjecting the piston proper, which is obviously 100 the cylindrical rim of each piston-wheel, to an internal pressure opposed by counteraction to the external pressure exerted by the steam occluded in the steam-space. The precise manner in which this internal counteractive pressure is secured is susceptible of variation between widely-separated limits, as I will hereinafter show; but a simple manner of accomplishing the desired end consists in forming each piston-wheel with a cylindrical rim or piston proper, 16^a, encircling a medially-disposed web 17, having a hub 18 pierced by and secured upon a shaft, as shown. 110 This form of piston-wheel will present an open-ended cylindrical piston adapted for the introduction or insertion of what may be termed "internal" steam-chests 19 and 20, extended into each end of each end piston from each of the casing-heads, the inner ends of the chests terminating at or adjacent to 115 the web of the wheel, as shown more clearly in Fig. 5 of the drawings. In cross-sectional contour the internal valve-chests are generally arcuate, inasmuch as they must fit snugly against the interior face of the piston 120 and must be so formed as not to contact with the adjacent hub. Each of these chests is provided with a steam-chamber 21, the outer side or wall of which is cut away and is closed 125 130 135

by the piston in order that the steam within the chest will exert a pressure directly against the interior face of the piston at a point opposite the external pressure exerted by the steam within the steam-space. Obviously, therefore, as the steam-chest is carried by a stationary part of the structure counteractive pressure will be exerted upon the piston of each end wheel and the several pistons will be relieved of the friction due to side thrusts and will all be balanced to facilitate the translation of a maximum percentage of the energy exerted by the motive agent. In like manner if the invention is embodied in a pump or compressor wherein the fluid instead of acting upon the pistons is acted upon thereby the beneficial result will be the same, inasmuch as counteractive pressures are exerted to the same end, whether they are direct or back pressures. So far as this broad aspect of the invention is concerned it is immaterial how the steam or other motive agent is introduced to the steam-chest or to the steam-spaces; but in Fig. 1 of the drawings I have shown a construction which comprehends the initial introduction of the steam to the chambers 21 of the valve-chests through main induction-ports 22 and 23, piercing both heads of the engine-casing and in communication with the steam-supply pipes. In this form the steam is led from the chambers 21 through piston-ports 24 and 25, piercing the walls of the pistons and opening into the recesses provided for the reception of the heads upon the center wheel. The steam is not permitted to escape to the steam-passages except when the piston-ports arrive opposite the open sides of the steam-chests, which latter are therefore so positioned that the induction of the steam to the steam-spaces will occur just as the heads have left the recesses in the end pistons and have entered the steam-spaces. This peculiar arrangement is also productive of another useful result, as it will be seen that the steam is cut off as soon as the recess is closed by being moved into opposition to that part of the contiguous head-block which is in contact with the periphery of the piston, and after the recess passes the head-block the piston-port will have passed the opening of the steam-chest and will consequently remain out of communication with the steam-supply until it again arrives at the end of the steam-passage. Therefore the period of steam-induction to the steam-spaces is of brief duration, and as a consequence the steam will be used expansively through a considerable portion of the movement of each head.

In Fig. 2 of the drawings I have shown a variation of the structure just described; but aside from the mere addition of a number of heads upon the center wheel a corresponding number of peripheral recesses and ports in the end wheels and changes of proportion necessitated thereby the variation only embraces the addition of controlling-valves 26 and 27 within the steam-chests and of an aux-

iliary steam-induction port 28 in one of the steam-spaces, said port being provided merely for the purpose of starting the engine in the event of its having stopped in a position which will leave all of the piston-ports out of communication with the chambers of the valve-chests. The controlling-valves 26 and 27 slide within the chambers 21 and are designed to control the closure of the main induction-ports 22 and 23 for the purpose of regulating the supply of steam or other motive agent to the engine. The particular means employed for actuating these valves is not essential; but such means may comprehend a rock-shaft 28, carrying an oscillating arm 29, engaging a recess in the valve and designed to be operated in any suitable manner—as, for instance, by governor mechanism which, in a manner well understood in the art, will control the position of the valve and insure such regulation of the steam-supply as will economize the consumption of the motive agent by regulating the steam pressure in a manner corresponding to the load opposed to the engine or the work to be done thereby.

In Fig. 3 of the drawings I have illustrated a variation of the structure shown in Fig. 1 similar to that shown in Fig. 2, except that the controlling-valves are omitted and the steam instead of being led initially into the chambers of the valve-chests is led directly to the steam-spaces through induction-ports 30 and 31, piercing the head-block. In this form the internal steam-chests are provided with steam from the steam-spaces through supplemental ports 32 and 33, formed in the heads of the casing, as clearly shown in Fig. 3. It will be noted that the fundamental idea—to wit, the proper balancing of the end pistons—is subserved in each of its forms, the only distinction being that in the first two instances the steam is admitted initially to the internal steam-chests, from whence it is supplied to the steam-spaces surrounding the center piston, while in the last instance the motive agent is supplied directly to the steam-spaces and is thence led to the interior of the chests to secure the proper counteractive pressure.

In Fig. 4 of the drawings I have illustrated a still further variation, which consists in so greatly augmenting the number of heads upon the center wheel and the recesses in the end wheel as to produce, in effect, a series of wheels or pistons having intermeshing radial teeth. It will be noted that in this construction I do not depend upon the engagement of the teeth with each other to form the abutment. On the contrary, I form the outer faces of these teeth 34 of each wheel upon a true circle to cause them to abut and have steam-tight connection or contact with the peripheral face of the opposed piston-wheel.

Another feature of the invention which I consider important and which may be common to the several forms shown is the provision of what may be termed "wear-plates" 35, (best seen in Figs. 5 and 6 of the draw-

ings,) constituting end abutments extending from the heads of the casing and in steam-tight contact with the ends of the pistons and constituting the end walls of the steam-spaces.

- 5 The purpose of these wear-plates is to maintain the steam-tight relation through those periods of travel of the heads during which the latter are under steam-pressure and permitting the remaining portion of each piston 10 to move freely and with considerable clearance between them and the walls of the casing for the purpose of reducing the frictional area of the working parts of the engine to the minimum. It is evident that where these 15 wear-plates are employed the auxiliary ports 32 and 33 are formed therein instead of in the ends or heads of the casing.

From the foregoing it will appear that I have produced a simple and effective translating device of the rotary-type embodying 20 one or any greater number of rotary members or pistons capable of running under even balance, and with the least possible opposition to the translation of energy exerted into 25 work performed; but while the present embodiment of the invention is believed at this time to be preferable I do not limit myself to the structural details illustrated and described, as it is evident that many changes, 30 modifications, and variations of both form, proportion, and arrangement may be effected as suggested by experience and experiment without departing from the scope of the protection prayed.

35 What I claim is—

1. A translating device comprising a casing and a series of rotary members mounted therein and geared together, means for supplying fluid to the interior of the casing intermediate 40 of said members to act on the peripheral faces thereof, and means for leading a fluid into contact with the interior faces of the end members only of the series at points opposite the application of external pressure to said 45 end members.

2. In a device of the character described, the combination with a casing provided with head-blocks and with bearing-plates carried by the opposite end walls of the casing, of rotary pistons located wholly out of contact 50 with the end walls of the casing and having peripheral contact with the head-blocks and bearing at their ends against the bearing-plates, said bearing-plates being disposed 55 across the opposite ends of the steam-space defined between the pistons, to confine the steam to such steam-space.

3. A translating device comprising a casing and a series of rotary pistons, the end pistons 60 of the series being hollow, means for supplying fluid to the interior of the casing intermediate of the pistons, stationary steam-chests extended into each of the end pistons of the series from opposite sides of the casing, and 65 means for supplying steam to the chests, each of said steam-chests having an open wall opposed to the interior face of its piston.

4. A translating device comprising a casing and a series of rotary pistons, the end pistons of the series being hollow, means for supplying fluid to the interior of the casing intermediate of the pistons, stationary steam-chests of transversely-arcuate form extended into each of the end pistons from the opposite sides of the casing, and means for supplying steam to said chests, each of said steam-chests having an open wall opposed directly to the interior face of its piston. 70

5. A translating device comprising a casing and a series of rotary pistons, the end pistons 80 of the series being formed with a central web and a cylindrical rim, means for supplying a motive fluid to the interior of the casing intermediate of the pistons, stationary steam-chests of transversely-arcuate form extended 85 into each of the end pistons from the opposite sides of the casing and terminating contiguous to the web, and means for supplying a motive fluid to the chests, each of said chests having an open wall opposed to the interior face of the adjacent piston-rim. 90

6. A translating device comprising a casing and a series of rotary pistons, the end pistons of the series being hollow, stationary steam-chests extended into the opposite ends of each 95 piston from the opposite sides of the casing, and ports establishing communication between the steam-chests and the steam-space defined intermediate of the pistons, each of said steam-chests having an open wall 100 opposed to the interior face of its piston.

7. In a translating device, the combination with a casing provided with head-blocks and bearing-plates, of rotary pistons located out of contact with the walls of the casing and having peripheral contact with the head-blocks, and bearing at their ends against the bearing-plates, and steam-chests extended into the ends of certain of the pistons and provided with open walls opposed to the interior face of the adjacent piston, certain of 110 said bearing-plates being provided with ports establishing communication between an interior steam-chest and the steam-space defined between contiguous pistons. 115

8. In a translating device, the combination with a casing, of a rotary center piston provided with heads, a pair of hollow end pistons geared to the center piston and provided with peripheral recesses for the reception of the heads, means for supplying a motive fluid to the interior of the casing intermediate of the pistons to act on the peripheral faces thereof, stationary steam-chests extended into the end pistons and having open 120 walls opposed to the interior faces thereof at points opposite the application of external pressure, and means for supplying steam to the steam-chests. 125

9. In a translating device, the combination 130 with a casing, of a rotary center piston there-in provided with heads, a pair of hollow end pistons geared to the center piston and provided with peripheral recesses for the reception

tion of the heads, means for supplying a motive fluid to the interior of the casing intermediate of the pistons, and stationary steam-chests extending into the end pistons and having open walls opposed to the interior faces thereof, said end pistons being provided with ports establishing communication between the interior of the casing and the interior of the steam-chests to permit the motive fluid to pass into the steam-chests for application to the interior faces of the end pistons at points opposite the application of external pressure to said end pistons.

10. In a translating device, the combination with a casing and means for supplying steam thereto, of a rotary center piston therein provided with heads, a pair of hollow end pistons provided with peripheral recesses for the reception of the heads, stationary steam-chests 15 extended into the end pistons and having openings opposed to the interior faces thereof, head-blocks located within the casing and defining steam-spaces for the passage of the heads, and means for supplying steam to said steam-chests.

11. A translating device comprising a casing and a rotary piston therein, means for introducing steam to the interior of the casing to operate the piston, and steam-chests 20 extending into the piston from the opposite sides thereof.

12. A translating device comprising a casing, and a rotary piston therein, means for leading steam to the interior of the casing, 25 transversely-arcuate steam-chests extending into the piston from the opposite sides thereof, and means for leading steam to the steam-chests.

13. In a translating device, the combination with a casing provided with stationary steam-chests extending inwardly from the opposite sides thereof and having open walls, a hollow piston located within the casing and having its peripheral wall disposed opposite the open 45 walls of said steam-chests, and means for leading steam to the casing and steam-chests respectively.

14. A translating device comprising a casing and a hollow piston therein, transversely-arcuate stationary steam-chests extended into the opposite ends of the piston from the opposite sides of the casing and having open walls opposed to the peripheral wall of said piston, and means for establishing communication 55 between the steam-chests and the interior of the casing whereby steam may be introduced into one of said chambers for the purpose of supplying both.

15. A translating device comprising a casing and a rotary piston therein formed with a central web and a cylindrical rim, and steam-chests extended into the opposite ends of the piston and bearing against the web thereof.

16. A translating device comprising a casing and a rotary piston formed with a central web and a cylindrical rim, stationary steam-

chests of transversely-arcuate form extended into the piston from the opposite sides thereof and bearing at their inner ends against the web, said steam-chests being provided with 70 open walls opposed to the interior face of the cylindrical rim of the piston, means for establishing communication between the casing and steam-chests, and means for leading steam into the casing. 75

17. A translating device comprising a casing and a plurality of pistons located wholly out of contact with the walls of the casing, bearing-plates opposed to the ends of the pistons and closing the opposite ends of the 80 steam-space defined between the pistons, a head-block having peripheral contact with the pistons, and means for introducing steam to the steam-space through the head-block.

18. A translating device comprising a casing and a plurality of pistons located wholly out of contact with the walls of the casing, bearing-plates opposed to the ends of the pistons and closing the opposite ends of the 85 steam-spaces defined between the pistons, a head-block having peripheral contact with the pistons, means for introducing steam to the steam-spaces through the head-block, and a stationary steam-chest extending into the piston and provided with an open wall disposed opposite the interior face of the piston- 90 rim.

19. A translating device comprising a casing and a plurality of pistons, a stationary steam-chest located within one piston, means 100 for introducing steam to the interior of the casing, and a port located beyond the end of the piston and communicating at its opposite ends with the interior of the casing and steam-chest respectively. 105

20. In a translating device, the combination with a casing and a piston, said piston being composed of a hub, a web and a cylindrical rim, of stationary steam-chests located between the hub and rim and abutting against the web of the piston. 110

21. A translating device comprising a casing, a series of rotary pistons arranged in alinement within the casing and moving in unison, means for supplying fluid to the interior of the casing intermediate of said pistons to act on the peripheral faces thereof, steam-chests mounted within the end pistons only of the series and having open walls opposed to the interior faces of said end pistons 115 at points opposite the application of external pressure thereto, and means for supplying steam to said steam-chests. 120

22. In a translating device, the combination with a casing provided with head-blocks, and with bearing-plates rigidly connected to the inner faces of the opposite end walls of the casing and disposed immediately adjacent to the head-blocks, of rotary pistons located wholly out of contact with the end walls of the casing and having peripheral contact with the head-blocks, and bearing at their ends 125 130

against the bearing-plates, said bearing-plates being disposed entirely across the opposite ends of the steam-space defined between the pistons to confine the steam to said steam-space and thus prevent the application of steam-pressure to the ends of the pistons.

In testimony that I claim the foregoing as

my own I have hereto affixed my signature in the presence of two witnesses.
